CLAIM

The ornamental design for a simulated wood panel, as shown and described.

DESCRIPTION

FIG. 1 is a top plan view of a simulated wood panel showing my new design;

FIG. 2 is a bottom plan view thereof;

FIG. 3 is a front elevation view thereof, the rear elevation being identical;

FIG. 4 is a left side elevation view thereof, the right side elevation being a mirror image;

FIG. 5 is a top plan view showing two adjacent simulated wood panels as they would appear in a position of use; and, FIG. 6 is a top plan view showing a plurality of simulated wood panels in various orientations.

The broken lines shown represent portions of the simulated wood panel that form no part of the claimed design.
